Phil. Rollhaus Design Fire Place.

N° 3548

PATENTED
JUN 15 1869

Charles Marsh
Gustav Dittmar

Inventor
Philip Rollhaus

United States Patent Office.

PHILIP ROLLHAUS, OF PORT CHESTER, NEW YORK.

Design No. 3,548, dated June 15, 1869.

DESIGN FOR A FIRE-PLACE HEATER.

The Schedule referred to in these Letters Patent and making part of the same.

To all whom it may concern:

Be it known that I, PHILIP ROLLHAUS, of Port Chester, in the county of Westchester, and State of New York, have invented a new and original Design for Fire-Place Heaters; and I do hereby declare that the following is a full, clear, and exact description thereof, which will enable others skilled in the art to make and use the same, reference being had to the accompanying drawing, forming part of this specification.

The present invention relates to a new and original design for a fire-place heater, which will be understood from the following description.

The accompanying photograph represents a perspective view of my fire-place heater.

In this case the fire-place heater is divided into four sections of different designs, numbered 1, 2, 3, and 4, consecutively.

M, No. 1, the base of the frame of the heater, has a raised vine, A, running around its top.

B B are ornamental doors in front of the ash-pit. The said doors have a raised bead, C, running around their outer edges. The part marked B is raised.

D represents a vine tapering to a point, top and bottom, as shown in photograph.

In the centre of the doors there is an open square, with a link, E, running horizontally, the sides of the link being connected to the top and bottom of the open square.

F F are two ovals, formed of a bead of raised pearls, and inside the said ovals there are two shields G G, cross-barred.

H is a shelving flange, smaller than the base.

This flange separates section No. 1 from section No. 2, and has a bead or raised pearl around the upper portion of its outer edge, and a vine, I, running around near the heater.

J J J represent three coils, separating the diamond gratings K.

The border of the said gratings consists of a single raised bead of pearl, L, connected to the scallops M.

N is a smaller flange than H, of similar construction, separating section 2 from section 3.

In section 3 the letter P represents open places.

Q is a bead, formed of three rows of pearl, the centre row being largest.

R are vines over the arch of each of the openings P; and

S are vines over each arch, running from a scallop in the centre between the arches.

S' are scrolls on the bottom of the plates S'.

T T are standing vines on each side of the heater.

In section No. 4, which represents the hood or cap of the heater, the door U is made with a round bead around it, and on each side of the door there is a triangle, formed of a raised bead of pearl, x, with an ornamental scallop extending outward from each point, and in the centre of each triangle there is a raised mound, with a raised ring around the same.

The frame W has a diamond bead, V, around its outer edge. The upper portion of the said frame is semicircular.

In section 2 the whole grating is made slightly convex.

In section 3 the plates S' are perpendicular as high as the handles X, from whence they bend gracefully inward to the point marked Y, and from thence perpendicular to the top.

Having thus described my invention,

I claim as new, and desire to secure by Letters Patent—

A new and original design for a fire-place heater, as herein set forth and described.

The above specification of my invention signed by me, this 12th day of May, 1869.

PHILIP ROLLHAUS.
